UNITED STATES PATENT OFFICE.

WILLIAM M. BUTLER, OF SYRACUSE, NEW YORK.

SECTIONAL BOILER.

1,089,747.

Specification of Letters Patent. Patented Mar. 10, 1914.

Application filed January 23, 1912. Serial No. 672,878.

To all whom it may concern:

Be it known that I, WILLIAM M. BUTLER, of Syracuse, in the county of Onondaga, in the State of New York, have invented 5 new and useful Improvements in Sectional Boilers, of which the following, taken in connection with the accompanying drawings, is a full, clear, and exact description.

This invention relates to certain improvements in sectional boilers for steam or hot water in which the hollow upright end and intermediate sections are mounted side by side upon a suitable supporting base and connected for continuous circulation of the 10 water or steam therethrough from one to the other and are also provided with communicating fire passages for continuous circulation of the products of combustion, the front portions of the intermediate sections 15 extending upwardly and forwardly from the rear of the fire box to a plane directly over the front of the fire box so as to form with the front section a fire pot having an inlet in its upper side.

20 The main object is to provide the upright hollow sections with registering openings constituting an auxiliary combustion chamber communicating through relatively small 25 passages with the main combustion or fire pot some distance below the fuel inlet so as to produce a down draft across the surface of the fuel and into the auxiliary combustion chamber for increasing the combustion of the gases, thereby obtaining a 30 greater heat efficiency from a given quantity of fuel.

Another object is to cause the highly 35 heated products of combustion in the auxiliary combustion chamber to traverse relatively large areas of all of the sections and return before escaping to the stack or chimney and to make the walls of the fire passages relatively shallow so as to cause the 40 water to absorb a maximum degree of heat in transit from the auxiliary chamber to such stack or chimney.

45 Other objects and uses relating to specific parts of the boiler will be brought out in the following description.

50 In the drawings Figure 1 is a perspective view of my improved boiler partly broken away to show more clearly the combustion chamber and fire passages. Fig. 2 is a horizontal sectional view through the lower portions of the boiler sections taken on line

2-2, Fig. 1, the central portions thereof being broken away and the grate and underlying base being omitted. Fig. 3 is a transverse vertical sectional view of the same boiler taken on line 3-3, Fig. 1 showing particularly the interior construction and relation of the intermediate section and front section. Fig. 4 is a horizontal sectional view of the boiler taken in a plane just above the top of the front section showing particularly the connection between the fire passages of the several sections. Figs. 5 and 6 are perspective views of opposite sides of one of the intermediate sections of the boiler. Figs. 7 and 8 are perspective 60 views respectively of the left-hand end and right-hand end sections of the boiler. Fig. 9 is a perspective view of the front boiler section.

The boiler proper is mounted upon a hollow rectangular supporting base —1— having a suitable ash-pit —2— and grate —3— together with a door —4— for the removal of ashes, said boiler comprising hollow upright end and intermediate sections —5—, 65 —6— and —7— and a hollow front section —8—. The boiler sections —5—, —6— and —7— are arranged side by side in close juxtaposition and are provided near their lower and upper sides with intercommunicating passages—formed by connecting nipples —10— which are seated in correspondingly tapered openings in the adjacent portions of the sections to form water tight joints, and also for receiving suitable clamping bolts —11— by which the sections are 70 tied together and held in operative relation.

The distributing system (not shown) may be connected in any suitable manner to the 75 upper and lower portions of the hollow boiler sections for the upflow and return of the heating fluid such as steam or hot water. The hollow sections —5—, —6— and —7— are preferably made of cast metal 80 having relatively thin walls of large area exposed to the heat and are comparatively shallow transversely of their surfaces of greatest area so as to allow the heat to be more quickly absorbed by the water therein 85 or rather for the purpose of more quickly raising the temperature of such water. The front section —8— is therefore of substantially the same length from side to side as the combined widths of the intermediate 90 95 100 105 110

sections —7— and is connected near its lower edge with the interiors of the end sections —5— and —6— by nipples —10— similar to those employed for connecting the intermediate sections —7— with the end sections, said front section being secured in place to the front portions of the end sections by means of clamping bolts —12— as best seen in Figs. 1 and 2. The intermediate sections —7— are substantially triangular and arranged with their wider portions at the top and with one angle resting upon the base —1— at the rear of the grate —3— so that their front edges incline upwardly and forwardly to overhang the grate and to form with the front section —8— a fire box or fuel chamber —13—, the upper front portions of said intermediate sections being disposed in substantially the vertical plane of the front sides of the grate. The front section —8— has its lower edge resting upon the base —1— at the front of the grate and inclines upwardly and forwardly therefrom but at a less angle than that of the front edges of the intermediate sections so that the lower portion of the fire box is of greater depth from front to rear than the upper portion, the vertical height of the section —8— being slightly less than that of the sections —5— and —6— and its intermediate portion is spaced apart from the front edges of the intermediate sections to form a fuel inlet —14— which is normally covered by a lid —15— as best seen in Figs. 1, 3, 4 and 8. The end sections —5— and —6— are of substantially the same form at the top and back as the intermediate sections —7— but extend forwardly some distance beyond the front edges of the lower portions of said intermediate sections to the front side of the grate and preferably across the ends of the front section —8— to which they are secured, thereby forming the end walls of the fire box or main combustion chamber, the top of the front section —8— being extended rearwardly against the front edges of the upper portions of the intermediate sections to form a gas tight joint therewith.

50 The lower front portions of the intermediate sections are provided with openings —16— registering with each other to form an auxiliary combustion chamber and upwardly and forwardly inclining water legs —17— which are comparatively shallow from front to rear and are provided with one or more, in this instance two, vertically elongated slots or fire passages —18— connecting the main and auxiliary combustion chambers —13— and —16—. These water legs —17— are comparatively shallow from front to rear and by forming the vertically elongated fire passages —18— therethrough, it is evident that 65 the water in the portions of the sections

is split up into relatively small bodies and therefore quickly heated by reason of the large area exposed to the heat on all sides. These fire passages —18— connecting the main and auxiliary combustion chambers 70 are located some distance below the fuel inlet and therefore there is always more or less draft from the inlet downwardly and rearwardly across the surface of the fire tending to accelerate the ignition and consumption of any gases which may accumulate in the auxiliary combustion chamber —16—, thus producing a maximum degree of heat with a minimum quantity of fuel. For a like purpose, the upper front portions 80 of the intermediate sections are provided with laterally extending registering openings —19— therethrough communicating with their respective openings —16— through suitable passages —20— in corresponding sides thereof as best seen in Figs. 4 and 6, thereby permitting the products of combustion to pass from the fire box through the passages —18— into the auxiliary fuel chamber —16— and thence through the passages —20— into the openings —19—, the 85 passages —20— being formed by making these portions of the hollow sections somewhat thinner than the remaining portions, still leaving communicating passages for 90 the water. In practice, however, the branch passages as —21— connecting the openings —19— with the main passages —20— are somewhat constricted by hollow flanges —22— which project partially across the 95 front sides of the passages —20— as shown more clearly in Fig. 4, thus retarding in a measure the too free escape of the products of combustion into and from the openings —19—. In like manner the rear upright 100 portions of the intermediate sections are provided with horizontally extending registering openings —23— forming a continuous flue from end to end and communicating at one end with the corresponding end of the flue formed by the openings —19— through a passage —24— in the adjacent end section —6— as shown more clearly in Fig. 4, said end section being provided on its inner side with branch openings —25— 105 and —26— registering respectively with the openings —19— and —23— in the adjacent intermediate section —7—.

The fire passage —24— is preferably formed in the section —6— midway between its inner and outer faces, leaving relatively shallow water chambers at opposite sides thereof so as to additionally expedite the heating of the water therein, said section being also provided in its outer side with 110 clean-out openings —27— and —28— which are normally covered by removable caps —29— and —30—, as shown more clearly in Fig. 4.

The end section —5— is substantially flat 115

and shallow transversely and is provided with an outlet —31— communicating with the opening —20— in the adjacent intermediate section —7— and adapted to be connected by suitable pipes to a chimney, not shown.

In operation the fuel is inserted in the inlet opening —14— and gravitates downwardly onto the grate between the front section —8— and front edges of the intermediate sections —7— and when ignited and burning, the products of combustion escape from the surface of the fuel through the passages —18— and into the auxiliary combustion chamber —16— where the gases from the fuel are consumed and the resultant products of combustion continue their transit as indicated by the arrows in Figs. 1 and 4 upwardly from the passages —20—, branch passages —21— and into the flue and openings —19— and thence laterally through said flue openings and passage —24— into the flue openings —23— and out to the chimney. In this manner, the heated products are caused to travel vertically and forwardly between the sections and thence horizontally from side to side and rearwardly at one end and return horizontally through the opposite flue openings —23— to the chimney, the return flues being located at the front and rear of the up-flow passages as shown more clearly in Fig. 4.

It will be seen from this construction that the bodies of water in the several sections are split up into relatively small quantities which are exposed to relatively large heating areas and that by causing the heated products to flow upwardly between the horizontal return flues, I am enabled to produce a rapid conversion of the water into steam when steam is required or a rapid heating and circulation of hot water when the latter is employed as the heating medium. It is also evident that the boiler may be built up or reduced at will by multiplying or reducing the number of intermediate sections, the end sections being the same for all boilers although the front section must be adapted for the particular size of boiler with which it is to be used.

What I claim is:

1. An upright boiler section having a rear upright water-leg and a hollow water-front inclining upwardly and forwardly from the base of the water-leg and portions thereof spaced apart therefrom to form an intervening combustion chamber, said inclined water-front communicating with the water-leg above and below said combustion chamber and provided with a fire passage therethrough from front to rear and surrounded by water space.

2. A sectional boiler comprising a base having an ash-pit and grate, hollow up-

right end and intermediate sections secured together side by side and having communicating water chambers, the front edges of the intermediate sections inclining upwardly and forwardly from the rear edge of the grate, and front sections resting upon the base and inclining upwardly and forwardly therefrom at the front side of the grate and connected to the end sections to form therewith and with the front edges of the intermediate sections a fire box, the lower front portions of the intermediate sections being provided with horizontally extending fire passages registering with each other to form an auxiliary combustion chamber, the portions of the intermediate sections between said fire passages and fire pot being provided with vertically elongated fire passages connecting the fire box with the auxiliary combustion chamber, said intermediate sections being also provided with upright fire passages in corresponding sides thereof and with separate sets of openings therethrough at opposite sides of the upright passages, those of each set registering with each other to form flues, one of the end sections being provided with a fire passage connecting the adjacent ends of the flues.

3. An upright boiler-section having a rear upright water-leg and a hollow water front inclining upwardly and forwardly from the base of the water-leg and having portions thereof spaced apart therefrom to form an intervening combustion chamber, said inclined water-front communicating with the water-leg above and below the combustion chamber and provided with a fire passage therethrough from front to rear and surrounded by water space, the water-leg being provided with a transverse fire passage therethrough from side to side.

4. A boiler comprising hollow upright end and intermediate sections arranged side by side, and a hollow upright front section secured to the end sections, the front edges of the intermediate sections being inclined downwardly and rearwardly at an angle with the rear face of the front section, upright passage-ways through the intermediate sections and connecting with a horizontal passage-way, vertical channels in said sections connecting said horizontal passage-way with a second passage-way, and a third passage-way connected to the second by a passage through one end section.

5. A boiler comprising hollow upright end and intermediate sections arranged side by side, and a hollow upright front section secured to the end sections, the front edges of the intermediate sections being inclined downwardly and rearwardly at an angle with the rear face of the front section to form a fire box gradually increasing in width from front to rear from top to bottom, the intermediate sections having front

and rear sets of registering fire flues, and an intermediate set of registering openings forming an auxiliary combustion chamber, at the rear of the fire box, said intermediate sections also having one set of passages connecting the fire box and combustion chamber and another set of passages connecting such chamber with the front set of flues, one of the end sections having a passage connecting the adjacent ends of the front and rear flues.

6. A sectional boiler comprising rear, hollow, intermediate and end sections and a front hollow section, all connected for the continuous passage of water, openings through each intermediate section registering to form flues, one of said flues in direct connection with the fire-pot, a second in direct connection with the first, and a third flue connected with said second flue by a passage through an end section.

7. A sectional boiler comprising hollow, intermediate and end sections and a front hollow section, all connected for the continuous passage of water, openings through each intermediate section registering to form flues, two of said flues extending over the fire-pot and one of them in direct connection therewith, and a third flue connected with one of the first flues by a passage through an end section.

8. A sectional boiler comprising intermediate and end sections arranged side by side and a hollow upright front section secured to the end section, the intermediate sections having lower front, upper front and rear flues, the lower front flue directly connected to the fire-pot and to the upper front flue, the upper front flue connected to the rear flue by a passage through an end section.

9. An upright boiler-section having a rear upright water-leg and a hollow water-front inclining upwardly and forwardly from the base of the water-leg and having portions thereof spaced apart therefrom to form an intervening combustion chamber, said inclined water-front communicating with the water-leg above and below the combustion chamber and provided with a fire passage therethrough from front to rear, the water-leg being provided with a transverse fire passage therethrough from side to side, a portion of the hollow section in front of the water leg and above the combustion chamber being provided with a transverse fire passage surrounded by water space and communicating with the combustion chamber.

10. An upright sectional boiler comprising an ash box, a grate across the upper side of the ash box, hollow upright end and intermediate water-sections mounted side by side upon the ash box, the intermediate sections having upright water-legs resting on

the ash box at the rear of the grate, said intermediate sections also having upwardly and forwardly inclined hollow water-fronts overhanging the grate from front to rear, portions of said water fronts being spaced apart from the water legs to form an intervening combustion chamber, said water fronts forming the rear side of a fire box and provided with a fire passage connecting the fire box with the combustion chamber, an additional water-front extending upwardly from the front of the grate some distance above the fire passages in the water-front of the intermediate sections and connected to the end sections, said additional water-front being spaced some distance apart from the front edges of the intermediate sections and forming therewith a fuel inlet some distance above the fire passages.

11. A section for a boiler comprising a hollow substantially triangular shell, a vertical passage-way therethrough leading to a horizontal flue, said flue connected to another flue by an upright channel in said shell, a third horizontal flue unconnected with the first two, and openings to the interior of said shell.

12. A section for a boiler comprising a metal shell member for the passage of water, said section divided into narrow water-tight passages by a vertical opening through the fire-pot side leading to a horizontal opening, said horizontal opening connected to a second horizontal opening by a vertical channel, and a horizontal opening near the rear wall of said shell.

13. A sectional boiler comprising upright end and intermediate water-sections connected side by side for intercommunication and forming the ends and rear side of a fire box, portions of the front sides of the intermediate sections being spaced apart from the rear portions to form a combustion chamber and provided with fire passages therethrough connecting said combustion chamber with the fire box and surrounded by water space, a separate water-section forming the front of the fire box and having a fuel inlet some distance above said fire passages, said water-front being connected to the end sections for intercommunication therewith.

14. A sectional boiler comprising a base, a grate on the base, upright end and intermediate water sections rising from the base at the ends and rear side of the grate, the intermediate sections having their front portions inclined upwardly and forwardly from the grate and portions thereof spaced apart from their rear portions to form an intervening combustion chamber and provided with fire passages connecting said combustion chamber and surrounded by water space with the fuel chamber and a

hollow water-front section rising from the base at the front of the grate and extending some distance above the fire passages and spaced apart from the front sides of the intermediate sections to form an intervening fuel magazine extending from the grate to the top of the front section.

In witness whereof I have hereunto set my hand on this 22nd day of January 1912.

WILLIAM M. BUTLER.
